COMBINED BOW TIE DISPLAY AND SHIRT COLLAR SHAPER

Leon P. Lerner, New York, N. Y.

Application March 18, 1952, Serial No. 18,946

Term of patent 3½ years

(Cl. D80—5)

To all whom it may concern:

Be it known that I, Leon P. Lerner, a citizen of the United States of America, residing in New York city, county of New York, and State of New York, have invented a new, original, and ornamental Design for a Combined Bowtie Display and Shirt Collar Shaper, of which the following is a specification, reference being had to the accompanying drawing, forming part thereof, wherein,

Figure 1 is a plan view of a combined bowtie display and shirt collar shaper showing my new design.

Figure 2 is a top edge elevational view thereof. The rear of the design is substantially plain in appearance.

I claim:

The ornamental design for a combined bowtie display and shirt collar shaper, substantially as shown and described.

LEON P. LERNER.
